UNITED STATES PATENT OFFICE.

ROBERT D. LOOSE, OF SPRINGFIELD, ILLINOIS.

AUXILIARY MIXER FOR INTERNAL-COMBUSTION ENGINES.

1,115,699.

Specification of Letters Patent.

Patented Nov. 3, 1914.

Application filed April 30, 1912. Serial No. 694,224.

To all whom it may concern:

Be it known that I, ROBERT D. LOOSE, a citizen of the United States, and a resident of Springfield, in the county of Sangamon and State of Illinois, have invented certain new and useful Improvements in Auxiliary Mixers for Internal-Combustion Engines; and I do hereby declare that the following description of my said invention, taken in connection with the accompanying sheet of drawings, forms a full, clear, and exact specification, which will enable others skilled in the art to which it appertains to make and use the same.

This invention has general reference to improvements in auxiliary mixers for internal combustion or explosive motors, and it consists, essentially, in the novel and peculiar combination of parts and details of construction as hereinafter first fully set forth and described, and then pointed out in the claims.

In the drawings, to which reference has already been made, Figure 1 is a perspective view of my invention and Fig. 2 a plan thereof. Fig. 3 is a similar view of a flat blank employed in my invention, and Fig. 4 an edge view of the same. Fig. 5 is a vertical section of my invention as installed 30 in a manifold of a hydrocarbon motor.

Like characters or symbols of reference are employed to designate similar parts in all the figures of the drawing.

It is a well known fact that while carburetors now used in motors of this class perform their functions of volatilizing the hydrocarbon in a more or less perfect manner under proper conditions, yet, under widely variant circumstances, there is room for vast improvement in this respect. A carburetor functioning perfectly under normal conditions, under unusually applied loads upon the motor, or a sudden acceleration of speed of the same, or under adverse atmospheric conditions, will permit charges, in which the constituent elements of mixture have not been thoroughly commingled or united, to pass into the intake pipe leading to the motor cylinders, with the resultant misfires or flooding the cylinders with unvolatilized hydrocarbons.

The essence of my invention, therefore, resides in the provision of means for thoroughly intermingling, commingling, and uniting the elements of the explosive mix-

ture after it leaves the carburetor and before it enters the cylinders of the motor. I accomplish this result by first cutting, dividing, or separating, as it were the charge as it leaves the carburetor, into a plurality of distinct and separate entities. To these I impart a vortical or whirling motion in my mixer, and then permit them to recombine after passing therethrough. This whirling motion, once established, will continue in the flow of the mixture and results in a more intimate union, and a more thorough intermingling, of the constituent elements thereof, than is otherwise possible. Moreover, the particles of liquid hydrocarbon carried through the carburetor in suspension are separated by this continuous whirling action, and their union with the oxygen accelerated.

Other objects of my invention are the production of mixers which can be applied to existing motors without disarranging any of the present parts or mechanism, and capable of being attached by the merest tyro; and, which can be cheaply and efficiently manufactured.

In Figs. 1, 2, and 3 I illustrate how my mixer A is formed from a flat, metallic strip B. The vanes 6 are pierced out from and bent up at right angles to the plane of the strip B, and the flange C is notched along its edges and bent back. The strip B is then passed through a special pair of rolls, made for the purpose, and shaped into cylindrical form, with the vanes 6 projecting inwardly from the interior and the flange C exteriorly from the exterior thereof. This completes the mixer, which is adapted to be introduced directly into the intake pipe F of a motor, its flange C being clamped between the flange F' of said intake and a flange C' of a carburetor G, all as clearly illustrated in Fig. 5. It will thus be seen that my mixer can be attached to any existing motor by simply separating the intake and carburetor flanges, slipping my mixer into the intake, and then rebolting said flanges together.

In cases where the interior of the intake pipe has irregularities or inequalities in the casting, which would otherwise prevent the insertion of the mixer A therein, the same may be slightly squeezed together to pass the obstruction, and when beyond the same, the natural spring in the mixer will tend

to spread the same apart and cause it to closely adhere to the interior of the intake pipe.

Having thus fully described my invention, 5 I claim as new and desire to secure unto myself by Letters Patent of the United States:

1. A flat metallic blank having a plurality of parallel vanes formed integrally therewith, said blank being adapted to be shaped 10 into a cylindrical shell with said vanes extending interiorly thereof, there being an axial, circular opening through said shell formed by the inner edges of said vanes, the whole when so shaped constituting a mixer.

15 2. A flat metallic blank having a plurality of parallel vanes formed integrally therewith and spaced equidistantly apart, said blank being adapted to be shaped into a cylindrical shell with said vanes extending 20 interiorly thereof and equidistantly spaced about the inner circumference of said shell, there being an axial, circular opening through said shell formed by the inner edges of said vanes, the whole when so shaped 25 constituting a mixer.

3. A flat metallic blank having a plurality of parallel vanes formed integrally therewith, said blank being adapted to be shaped into a cylindrical shell with said vanes extending 30 interiorly thereof, there being an axial, circular opening through said shell formed by the inner edges of said vanes, the diameter of which opening is substantially 35 equal to the width of one of said vanes, the whole when so shaped constituting a mixer.

4. A flat metallic blank having a plurality of parallel vanes formed integrally therewith and spaced equidistantly apart, said blank being adapted to be shaped into a cylindrical shell with said vanes extending 40 interiorly thereof and equidistantly spaced about the inner circumference of said shell, there being an axial, circular opening through said shell formed by the inner 45 edges of said vanes, the diameter of which opening is substantially equal to the width of one of said vanes, the whole when so shaped constituting a mixer.

5. A flat metallic blank having a plurality 50 of parallel vanes formed integrally therewith and arranged obliquely to the longitudinal edges thereof, said blank being adapted to be shaped into a cylindrical shell with said vanes extending 55 interiorly thereof in helical disposition, there being an axial, circular opening through said shell formed by the inner edges of said vanes, the whole when so shaped constituting a mixer.

60 6. A flat metallic blank having a plurality 65 of parallel vanes formed integrally therewith, arranged obliquely to the longitudinal edges thereof, and spaced equidistantly apart, said blank being adapted to be shaped 70 into a cylindrical shell with said vanes ex-

tending interiorly thereof in helical disposition and equidistant spacing about the inner circumference of said shell, there being an axial, circular opening through said shell formed by the inner edges of said 75 vanes, the whole when so shaped constituting a mixer.

7. A flat metallic blank having a plurality of parallel vanes formed integrally therewith and arranged obliquely to the longitudinal edges thereof, said blank being adapted to be shaped into a cylindrical shell with said 80 vanes extending interiorly thereof in helical disposition, there being an axial, circular opening through said shell formed by the inner edges of said vanes, the diameter of which opening is substantially equal to the width of one of said vanes, the whole when so shaped constituting a mixer.

8. A flat metallic blank having a plurality of parallel vanes formed integrally therewith, arranged obliquely to the longitudinal edges thereof, and spaced equidistantly apart, said blank being adapted to be shaped into a cylindrical shell with said vanes extending 85 interiorly thereof in helical disposition and equidistant spacing about the inner circumference of said shell, there being an axial, circular opening through said shell formed by the inner edges of said vanes, the diameter of which opening is substantially 90 equal to the width of one of said vanes, the whole when so shaped constituting a mixer.

9. A flat metallic blank having a plurality of parallel vanes pierced from and bent up 100 at right angles to the plane thereof, said blank being adapted to be shaped into a cylindrical shell with said vanes extending interiorly thereof, there being an axial, circular opening through said shell formed by the inner edges of said vanes, the whole when so shaped constituting a mixer.

10. A flat metallic blank having a plurality of parallel vanes pierced from and bent up 105 at right angles to the plane thereof and spaced equidistantly apart, said blank being adapted to be shaped into a cylindrical shell with said vanes extending 110 interiorly thereof and equidistantly spaced about the inner circumference of said shell, there being an axial, circular opening through said shell formed by the inner edges of said vanes, the whole when so shaped constituting a mixer.

11. A flat metallic blank having a plurality of parallel vanes pierced from and bent up 115 at right angles to the plane thereof, arranged obliquely to the longitudinal edges of said blank, and spaced equidistantly apart, said blank being adapted to be shaped into a cylindrical shell with said vanes extending interiorly thereof in helical disposition and equidistant spacing about the inner circumference of said shell, there being an axial, circular opening through said 120

shell formed by the inner edges of said vanes, the whole when so shaped constituting a mixer.

12. A flat metallic blank having a plurality of parallel vanes pierced from and bent up at right angles to the plane thereof, said blank being adapted to be shaped into a circular shell with said vanes extending interiorly thereof, the whole when so shaped 10 constituting a mixer.

13. A flat metallic blank having a plurality of parallel vanes pierced from and bent up at right angles to the plane thereof and spaced equidistantly apart, said blank 15 being adapted to be shaped into a cylindrical shell with said vanes extending interiorly thereof and equidistantly spaced about the

inner circumference of said shell, the whole when so shaped constituting a mixer.

14. A flat metallic blank having a plurality of parallel vanes pierced from and bent up at right angles to the plane thereof, arranged obliquely to the longitudinal edges of said blank, and spaced equidistantly apart, said blank being arranged to be 20 shaped into a cylindrical shell with said vanes extending interiorly thereof in helical disposition and equidistant spacing about the inner circumference of said shell, the whole when so shaped constituting a mixer. 30
